CLAIM

The ornamental design for a desk, as shown and described.

DESCRIPTION

FIG. 1 is a top, front perspective view of a desk showing my new design;

FIG. 2 is a bottom, rear perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the encircled portion taken from FIG. 1.

The broken lines shown in the drawings depict portions of the desk in which the design is embodied that form no part of the claimed design.
